CLAIM

The ornamental design for a console with autonomous vehicle control buttons, as shown and described.

DESCRIPTION

The present application is related to application Ser. No. 29/491,937, entitled Autonomous Vehicle Overall Interior; to application Ser. No. 29/491,870, entitled Autonomous Vehicle Storage Bin/Tray; to application Ser. No. 29/491,867, entitled Autonomous Vehicle Console, now U.S. Pat. No. D764,386; to application Ser. No. 29/491,868, entitled Autonomous Vehicle Seat; and to application Ser. No. 29/491,889, entitled Autonomous Vehicle Go/Pull Over Button, each of which is filed concurrently herewith, the entire disclosures of which are incorporated by reference herein. FIG. 1 is a rear perspective view of a console with autonomous vehicle control buttons according to our design; FIG. 2 is a front elevation view thereof; FIG. 3 is a side elevation view thereof;

FIG. 3 is a back elevation view thereof;
FIG. 4 is a right side elevation view thereof;
FIG. 5 is a left side elevation view thereof;
FIG. 6 is a top elevation view thereof; and,
FIG. 7 is a bottom elevation view thereof.
The features shown in broken lines are environmental only
and form no part of the claimed design.
As shown by the figures, the "GO" and "STOP NOW"
buttons are planar.

1 Claim, 5 Drawing Sheets
